UNITED STATES PATENT OFFICE.

BURT D. STEVENS, OF RIVERSIDE, ILLINOIS, ASSIGNOR TO THE MIEHLE PRINTING PRESS & MANUFACTURING COMPANY, OF CHICAGO, ILLINOIS, A CORPORATION OF ILLINOIS.

SUCTION CLEANING MECHANISM FOR PRINTING-PRESSES.

1,096,471.

Specification of Letters Patent. Patented May 12, 1914.

Application filed September 8, 1913. Serial No. 788,563.

To all whom it may concern:

Be it known that I, BURT D. STEVENS, a citizen of the United States, residing at Riverside, in the county of Cook and State 5 of Illinois, have invented certain new and useful Improvements in Suction Cleaning Mechanism for Printing-Presses, of which the following is a specification.

The paper sheet as it reaches the press 10 has upon its surface a considerable amount of dust such as paper fuzz which fills the type faces and otherwise interferes with the obtaining of a clear cut impression. It has been proposed to remove this dust previous 15 to the printing operation by wiping devices, brushes and by currents of air but the conditions prevailing in connection with the operation of printing presses and particularly of two-revolution presses have rendered these expedients as heretofore devised far from satisfactory.

The present invention has for its primary object the provision of a suction cleaning device acting upon the paper before 25 printing which device is so arranged as not to interfere with the feed or delivery and not to require to be intermittently cut out of action as has heretofore been the case.

A further object of the invention is the 30 employment of a suction device to perform a double service in clearing out or removal of the dust and shreds due to the slitting of the paper as it leaves the press.

With these objects in view the suction device 35 is arranged adjacent the cylinder periphery at a point immediately beyond the delivery and slitting mechanism instead of between the feed and delivery so that while the sheet of paper held by the grippers passes 40 through the space between the feed and delivery twice in a two-revolution press it passes the suction device but once and the latter does not therefore need to be cut out of operation at all as would be the case if 45 the suction cleaning device were arranged between the feed and delivery. This location of the suction cleaning device also enables it to act simultaneously upon both the surface of the paper on the press and the 50 trough of the slitting mechanism whereby both are kept clean.

In order that the invention may be readily understood a preferred embodiment of the same is set forth in the accompanying

drawing and in the description based thereon. As, however, the invention is capable of embodiment in other constructional forms the drawing and description are to be construed in an illustrative and not in an unnecessarily limiting sense.

In the drawing Figure 1 is a schematic view partly in section illustrating the invention as applied to a two-revolution press; and Fig. 2 is a fragmentary view of the mouth of the suction tube with its guard.

Herein the reference numeral 11 designates generally a printing cylinder and 12 the bed of a two-revolution press, the feed being shown at 13 and the delivery at 14. In a press of this character the sheet of 70 paper 15 is received from the feed by the grippers 16 and carried around with the cylinder receiving its impression from the bed 12 after which it again passes under the feed, traverses the space between the feed 75 and delivery a second time and is removed from the cylinder by the delivery. As the sheet leaves the press it is slit by the slitting mechanism, indicated at 17, at the delivery point, the shreds of paper and the like collecting within the trough 17^a from which it has usually been removed at intervals by hand.

In order to clean the sheet of paper from any dust adhering to the surface thereof and 85 also to remove the dust and shreds from the slitting trough I arrange at a point below the slitting mechanism a suction device including a draft tube 18 having two branches 19 and 20, the branch 19 having its mouth 90 arranged within the slitting trough 17 for removing the dust therefrom and the branch 20 having its mouth disposed adjacent the cylinder periphery to act upon the paper 15 in its path at a point immediately beyond the delivery. The lower wall of the branch tube 20 is cut away slightly so as to permit the air to enter the tube in a direction counter to that of the movement of the paper across its mouth and in order to 100 prevent the paper being sucked into the tube the mouth of the latter is protected by a grid comprising wires 21 extending across the same and also across the cut-away portion provided for the entry of the air.

It will thus be observed that the paper as it passes from the feed to the printing position is subject to the cleaning action of the

suction device and as it passes upon the next revolution to the delivery it is slit and the resultant shred dust is carried off from the slitting trough by the second mouth of the 5 same suction device.

At each alternate revolution of the cylinder 11 the suction device acts upon the bare face of the cylinder, there being no paper held by the grippers, and the action 10 of the suction device is ineffective but non injurious, whereas if the suction device were arranged in advance of the delivery between the same and the feed the paper would pass in front of the suction mouth 15 before being printed and also after printing before delivery which would necessitate the cutting of the suction cleaning device out of operation because of its injurious effect upon the freshly printed sheet.

20 I claim:

1. The combination with the cylinder of a printing press, the feed, and the delivery, of a suction cleaning device arranged to act upon the paper carried by the cylinder at a 25 point beyond the delivery, said device including a draft tube having a mouth terminating adjacent the cylinder periphery, and a grid over said mouth, the rear lip of the mouth cut away to permit the entry of 30 air in a direction counter to the movement of the cylinder, substantially as described.

2. The combination with the cylinder of a two-revolution printing press, the feed, and the delivery, of a suction cleaning device 35 arranged to act upon the paper carried by the cylinder at a point beyond the delivery, said device including a draft tube having its mouth terminating adjacent the cylinder, the rear lip of the mouth cut away 40 to permit the entry of air in a direction counter to the movement of the cylinder, substantially as described.

3. The combination with the cylinder of a printing press, the feed, the delivery, and 45 slitting mechanism, of a suction cleaning device arranged to act upon the paper carried by the cylinder at a point beyond the

delivery and also upon the slitting mechanism, substantially as described.

4. The combination with the cylinder of 50 a printing press, the feed, the delivery, and slitting mechanism, of a suction cleaning device arranged to act upon the paper carried by the cylinder at a point beyond the delivery and also upon the slitting mechanism, 55 said device including a draft tube having two mouths disposed one adjacent the cylinder periphery and the other adjacent the slitting mechanism, substantially as described.

60 5. The combination with the cylinder of a printing press, the feed, the delivery, and slitting mechanism, of a suction cleaning device arranged to act upon the paper carried by the cylinder at a point beyond the delivery and also upon the slitting mechanism, 65 said device including a draft tube having two mouths disposed one adjacent the cylinder periphery and the other adjacent the slitting mechanism, and a wire 70 grid over the first named mouth, substantially as described.

6. The combination with the cylinder of a printing press, the feed, the delivery, and slitting mechanism, of a suction cleaning device 75 arranged to act upon the paper carried by the cylinder at a point beyond the delivery and also upon the slitting mechanism, said device including a draft tube having two mouths disposed one adjacent the cylinder periphery and the other adjacent the slitting mechanism, the rear lip of the first 80 named mouth cut away to permit the entry of air in a direction counter to the movement of the cylinder, substantially as described.

85 In testimony whereof I have hereunto signed my name in the presence of two subscribing witnesses.

BURT D. STEVENS.
